JOHN H. STRINGHAM, OF JERSEY CITY, NEW JERSEY.

IGNITION DEVICE FOR EXPLOSIVE-ENGINES.

1,354,586.

Specification of Letters Patent.

Patented Oct. 5, 1920.

Application filed August 19, 1918. Serial No. 250,420.

To all whom it may concern:

Be it known that I, JOHN H. STRINGHAM, a citizen of the United States, residing in Jersey City, in the county of Hudson and State of New Jersey, have invented a certain new and useful Improvement in Ignition Devices for Explosive-Engines, of which the following is a specification.

The present invention relates to an improvement in ignition devices for explosive engines, and more particularly to an improvement in ignition devices of the kind adapted to receive a portion of the gases or products of combustion, hold this portion of heated combustion gas trapped or separate from the cylinder during the compression of the next explosive charge and then return it to the cylinder to ignite the charge, an ignition device of this type being disclosed in my Patent No. 1,203,072, granted October 31, 1916.

The object of the invention is to improve upon the construction and organization of ignition devices of the above type in order to produce a more simple and compact device, more efficient and durable in use, less expensive to manufacture, and, withal, more capable of effecting improved self-timed combustion. To the accomplishment of this object, the invention consists in the improved ignition device hereinafter described and particularly pointed out in the appended claims.

The preferred form of embodying the invention is illustrated in the accompanying drawings, in which Figure 1 is a vertical section of the improved ignition device; Fig. 2 is a side elevation of the same; and Figs. 3, 4, 5, and 6, are sections taken on the lines 3—3, 4—4, 5—5, 6—6, respectively, of Fig. 1.

The improved ignition device for explosive or internal combustion engines as illustrated in the drawings, comprises a lower body portion or valve casing 11 and an upper body portion or spring casing 12. These two parts together constitute the framework of the device and support the operative elements thereof. The valve casing 11 is threaded at its lower end so that it may be screwed into the cylinder of the engine to which the device is applied, and the spring casing 12 is screwed into the upper end of the valve casing 11. The ignition device is provided with a trap or chamber adapted to receive a portion of the gases or products of combustion during the explosion, and to

hold the trapped gas at its high temperature until the next explosive mixture is brought to a certain degree of compression by the piston, whereupon a valve is opened 60 to permit the trapped gas to enter the cylinder and ignite the compressed explosive mixture therein. The chamber for trapping the combustion gas is formed within the hollow head portion, which is the lower end 65 (Fig. 1) of a valve 4, slidably received within the valve casing 11. The gas chamber within the valve 4 is inclosed at its sides by a cylindrical wall or casing 13 fastened at its lower end to a lug or boss 14 projecting from 70 the bottom end of the valve casing 11. The gas chamber opens into the interior 15 of the valve casing 11, when the valve 4 is raised, through holes 3 in the bottom part of the gas chamber casing 13; and the interior of the valve casing 11 opens into the cylinder of the engine through holes 1 drilled in the closed bottom end of the valve casing. Suspended within the gas chamber is a perforated cylindrical sleeve 16 concentrically arranged with the casing 13. The interior of the sleeve 16 is filled with wire mesh 2. The casing or wall 13 of the gas chamber, the sleeve 16 and the wire mesh 2 are all composed of some heat-resisting material such as nichrome steel. This construction is for the purpose of keeping the trapped combustion gas at as high a temperature as possible. The valve 4 is normally held seated over the holes 1 to keep 90 the gas chamber closed, by means of a spring 5 interposed between a nut 17 screwed into the hollow stem 18 of the valve 4 and a nut 6 screwed into the end of the spring casing 12. The nut 17 virtually constitutes an extension of the valve stem 18. By adjusting the nut 6 the tension of the spring 5 may be regulated. The tension of the spring 5 will be such that the valve 4 will be opened only when the compression 95 of the explosive mixture in the cylinder is nearly at its highest point. The valve 4 is raised during the compression of the explosive mixture in the cylinder and is held raised during the explosion, so that a portion of the gases or products of combustion find their way through the holes 1 and 3 into the gas chamber where the gas is held trapped at its high temperature until substantially the culmination of the next compression stroke of the engine. The valve 100 4 is a double-acting valve seating itself at 105 110

its upper end when raised so as to prevent the escape of the compressed gases except through the holes 3.

In order that the gas chamber may be thoroughly cleaned out after each entrapment of combustion gas therein, a circular exhaust passage 9 formed in the lower end of the spring casing 12 surrounds the stem 18 of the valve 4. This exhaust passage 9 gives into the atmosphere through an outlet 18'. The escape of the gases through the outlet 18' is muffled by a screw 10. When the valve 4 is seated the exhaust passage 9 is covered over by the adjacent part of the stem 18, but when the valve 4 is at the limit of its upward movement, then the holes 19 extending radially from a valve chamber 20 register with the exhaust passage 9. The valve chamber 20 communicates with the gas chamber through a central hole 21 in the valve stem 18. The passage 21 between the valve chamber 20 and the gas chamber is normally held closed by a valve 7 slidingly received in the nut 17. The valve 7 is closed by a spring 8 (of higher tension than the spring 5) interposed between the nut 17 and a nut 22 screwed into the upper end of a casing 23 extended upwardly from the nut 17. The tension of the spring 8 may be regulated by adjusting the nut 22. The tension of the spring 8 is such that the compression of the explosive mixture in the cylinder does not effect an unseating or opening of the valve 7 when the valve 4 is unseated. When, however, the valve 4 has been opened to permit trapped, heated gas in the gas chamber to pass into the cylinder to explode the compressed explosive mixture, then the force of the explosion unseats the valve 7. There is now momentarily a free passage from the gas chamber into the atmosphere, so that the residue of gases remaining in the gas chamber are swept out therefrom by the passage of the fresh products of combustion therethrough. When the force of the explosion diminishes slightly the valve 7 is seated, and then as the force of the explosion continues to diminish the valve 4 seats itself, leaving some of the hot products of combustion trapped in the gas chamber.

The operation of the improved ignition device is as follows: When the engine is started up a spark plug is used to cause the initial explosion. The compression of the explosive mixture in the cylinder previous to the explosion has opened the valve 4 so that when the explosion takes place a small portion of the gases or products of combustion rush into the gas chamber. The valve 4 being at this time at the limit of its upward movement, and the force of the explosion having unseated the valve 7, there is a momentary escape of the combustion gases through the exhaust passage 9. The

amount of gas escaping through the exhaust passage 9 is just sufficient to insure that no stale air or gas remains in the gas chamber. The full force of the explosion having expended itself slightly, the valve 7 closes. 70 And thereafter when the force of the explosion diminishes below the compression point the valve 4 closes leaving the gas chamber full of trapped hot combustion gas. The exhaust of the explosion having been 75 completed, the explosive mixture is again compressed in the cylinder by the next up-stroke of the piston. When the compression of the explosive mixture has reached the pre-determined point the valve 4 is unseated, 80 permitting the hot and highly compressed combustion gas in the gas chamber to pass into the cylinder and ignite the compressed explosive mixture therein. The opening of the valve 7 during the explosion permits the 85 stale combustion gas still remaining in the gas chamber to be swept out of the passage by the fresh combustion gas therethrough. As the force of the explosion diminishes, the valves 7 and 4 successively close, trapping 90 some of the gases or products of combustion in the gas chamber, and thereafter the same series of operative steps as described above are repeated throughout the operation of the engine. 95

The ignition device described above is self-timed in its operation after the tension of the springs have once been regulated for the particular engine to which the device is applied; because when the load on the engine is increased, more gas is sucked into the cylinder, so that the pressure sufficient to open the valve 4 occurs sooner and the effect is accordingly equivalent to advancing the usual spark. 100

It will be understood that many changes may be made in the construction of the ignition device illustrated in the drawings and described above without departing from the spirit of the invention. The construction illustrated and described, however, greatly facilitates the ease and rapidity with which the work of manufacture may be carried on. Moreover, this construction provides a very durable and efficient ignition device. If at 110 any time it is necessary to get into the interior of the device for any purpose, the joined structure facilitates the taking apart and the putting together of the device. 115

Having thus described the invention, what 120 is claimed is:—

1. An ignition device for explosive engines comprising a gas chamber connected by passages with the cylinder of the engine and with the atmosphere, a valve in which the gas chamber is formed for normally closing the passage to the cylinder, and a valve for normally closing the passage to the atmosphere. 125

2. An ignition device for explosive en- 130

gines comprising a gas chamber having a passage connecting it with the cylinder of the engine and a passage connecting it with the atmosphere, a valve for normally closing the passage to the cylinder, and a second valve mounted within the first valve for normally closing the passage to the atmosphere.

3. An ignition device for explosive engines comprising a gas chamber having passages to the cylinder of the engine and to the atmosphere, a valve in which the gas chamber is formed for normally closing the passage to the cylinder, and a second valve mounted within the first valve for normally closing the passage to the atmosphere.

4. An ignition device for explosive engines comprising a gas chamber, a passage from the gas chamber to the cylinder of the engine, a passage from the gas chamber to the atmosphere, valves for normally closing the passages, said valves being opened respectively by the compression and by the explosion.

25 5. An ignition device for explosive engines comprising a valve casing adapted to be attached to the cylinder of the engine, a valve in the casing, a gas chamber in the valve, and a passage between the gas chamber and the cylinder normally closed by the valve.

6. An ignition device for explosive engines comprising a casing, a valve in the casing, a gas chamber in the valve, a passage between the gas chamber and the cylinder of the engine normally closed by the valve, and a passage between the gas chamber and the atmosphere normally closed by a second valve.

40 7. An ignition device for explosive engines having, in combination, a casing, a valve in the casing, a gas chamber in the valve, a passage between the gas chamber

and the cylinder of the engine normally closed by the valve, a second valve mounted 45 within the first valve, and a passage between the gas chamber and the atmosphere normally closed by the second valve.

8. An ignition device for explosive engines having, in combination, a valve casing, 50 a valve therein, a gas chamber within the valve constructed to retain and keep hot products of combustion, a passage between the gas chamber and the cylinder of the engine normally closed by the valve, a spring 55 for closing the valve, a passage between the gas chamber and the atmosphere, a second valve for normally closing this passage, and a spring located within the first spring for closing the second valve. 60

9. An ignition device for explosive engines comprising a gas chamber, a passage between the gas chamber and the cylinder of the engine through which products of combustion enter the gas chamber, a valve for 65 closing the gas chamber to keep the products of combustion therein, a passage between the gas chamber and the atmosphere, and a valve carried by the first valve for normally closing the passage to the atmosphere, the first valve being arranged to be 70 opened by the compression, and the second valve being arranged to be opened by the explosion.

10. An ignition device for explosive engines comprising a gas chamber, a passage between the gas chamber and the cylinder of the engine, a valve for normally closing the passage, a passage between the gas chamber and the atmosphere, a valve for 80 normally closing the passage to the atmosphere, and means for muffling the passage of exhaust gases from the chamber to the atmosphere. 75
